UNITED STATES PATENT OFFICE

FREDERICK TASKER BURGESS AND CHARLES WILLIAM SEWELL, OF CRICKLEWOOD, ENGLAND, ASSIGNORS OF ONE-THIRD TO BENTLEY MOTORS LIMITED, OF CRICKLEWOOD, ENGLAND, A BRITISH COMPANY

BRAKE FOR VEHICLES

Application filed August 29, 1928, Serial No. 302,816, and in Great Britain February 21, 1928.

This invention relates to brakes of the internal-expanding kind having a forward shoe which is applied by the cam and is connected by a floating pivot with a rearward shoe. Such brakes are generally known as servo shoe brakes.

A defect with this type of brake is that the two shoes are only located by the applying cam for the forward shoe and the abutment 10 for the rear shoe, which are close together, and consequently the shoes are liable to swing edgewise on rough roads and strike the drum at points about 90 degrees around the circumference from the location points.

15 To overcome this there is frequently employed a stop which engages the rear shoe towards the floating pivot end, but this stop requires adjustment every time the brake is adjusted in order that movement in the "off" 20 position of the rear shoe may not become excessive as the lining or drum wears.

The object of the present invention is to provide a simple system by which the foregoing defect is avoided, and as a result no adjustment is necessary until the brake requires 25 re-lining.

In the accompanying drawings, which show a preferred construction,

Figure 1 is an elevation, partly in section, 30 showing the brake applied, and

Figure 2, on a larger scale, is a fragmentary section on the line II-II of Figure 1.

In the construction shown, the applying cam 2 is at the top of the brake in engagement 35 with the forward shoe 3 and the abutment forming the location point for the rear shoe 4 is close to it. Preferably the rear shoe terminates in a peg or roller 5 which is held by the usual spring 6 against an ineffective, or 40 practically ineffective, surface 7 on the applying cam, so that comparatively little torque positive or negative is applied to the cam by the shoe 4.

The applying portion of the cam may be a 45 nose 8, of such an angle to give the most uniform motion, which is adapted to bear against the end of the forward shoe. At the bottom of the brake is the floating pivot 9 and this is supported by the swinging link 10 pivoted 50 at 11 to the anchor plate 12. The forward

shoe terminates in a jaw 13 which half embraces the pivot pin, whilst the other half of the pivot pin is embraced by a jaw 14 on the rear shoe, the two being held together by a spring 15 at each side of the swinging link 55 and connecting the two shoes. If desirable, clearance may be provided for the pin in the jaws. When the brake lining is unworn, the swinging link 10 hangs vertically, or approximately so, from the anchor plate, and integral 60 with the link is an arm 16 which preferably is radial to the axis of the pivot pin and which projects towards the forward shoe and is connected with it by a pin-and-slot or similar joint. 65

This arm is slightly resilient, and it may terminate in a rounded end 17 or roller which engages a slot 18 in a stud 19 which is carried non-rotatably as at 20 by the forward shoe 3 and whose position can be adjusted along a slot 21 therein. The direction of this slot is preferably at right angles to the normal position of the arm 16 and is approximately directed toward the axis of the applying cam 2. The stud 19 can be locked in any desired position in the slot 21, and for access to the locking nut 22 an aperture 23 is formed in the anchor plate of the brake, this being closed by a light cover 24. 70

In setting the adjustment, the lock nut 22 is slackened and the brake fully applied, which causes both shoes to bear against the brake drum 25. The lock nut is then tightened up, after which no further adjustment is necessary unless the brake is dismantled or 75 one of the linings altered.

When the brake is applied, the forward shoe 3 tends to travel round with the drum in the usual manner in the direction of the arrow 26, and applies the rear shoe by thrust through the floating pivot also in the usual manner. It may be that in this operation the arm 16 may bend slightly owing to the path of its rounded end, indicated by the arc 27, differing from the path around the brake of the slot engaged by it as indicated by the arc 28, it yielding under the considerable force of the brake application. Thus the link 10 and resilient arm 16 have little or no effect upon the brake application, which is practi- 80 85 90 95

cally the same as that which exists in ordinary brakes of this type.

If, however, the position of the applying cam 2 is adjusted angularly to take up backlash as the brake wear's such movement will obviously alter the "off" position of the forward shoe, and this in turn, through the action of the slot 18 upon the resilient arm 16, will move the floating pivot and push the rear shoe 4 slightly closer to the drum. In this way the "off" position of the rear shoe is controlled and swinging of the two shoes about the location points at the top of the brake is prevented by means of the flexible arm and its engagement with the guide slot on the shoe 3.

It is preferred that the contact between the rear shoe and the applying cam member (which, as shown at 7, is eccentric at the back) should be such that, as the cam is moved to apply the brake, it moves the rear shoe slightly in a contrary direction to that of usual rotation of the brake drum. This prevents excessive servo action and gives the additional amount of take up of the clearance between the rear shoe and brake drum, and also assists the braking effect when the vehicle is travelling backwards. In most servo shoe brakes the braking effect when travelling backwards is considerably less than when travelling forwards.

By this invention simple means is provided for locating the rear shoe and for enabling a single adjustment of the brake to do all that is required.

What we claim as our invention and desire to secure by Letters Patent of the United States is:—

1. In an internal expanding brake, the combination of a forward shoe, a rearward shoe, a floating pivot connecting the two shoes, means for applying said forward shoe, a swinging link supporting said floating pivot, an arm on the swinging link which has a sliding engagement with the forward shoe so arranged that there is no interference with the servo action of the brake, substantially as set forth.

2. In an internal expanding brake, the combination of a forward shoe, a rearward shoe, a floating pivot connecting the two shoes, means for applying said forward shoe, a swinging link supporting said floating pivot, an arm carried by said swinging link slidably engaging in guides provided on the forward shoe, and these guides are adjustable for position sideways, and a connection between said arm and said forward shoe such that the position of said link and thus of said floating pivot varies with the position of the forward shoe, substantially as set forth.

3. A brake as claimed in claim 2, in which guides are formed in a stud which is carried non-rotatably by the forward shoe and is adjustable along a slot therein in a direc-

tion which is at right angles to the normal position of the arm, substantially as set forth.

4. A brake as claimed in claim 2, in which movement of the guides to adjust them is approximately on a line directed to the axis of the applying cam, substantially as set forth.

5. In an internal expanding brake, the combination of a forward shoe, a rearward shoe, a floating pivot connecting the two shoes, an applying cam for said forward shoe, an anchor plate, a swinging link pivoted thereto supporting said floating pivot, an arm extending from said swinging link radially to said floating pivot and a sliding engagement between the end of said arm and said forward shoe acting in a direction substantially at right angles to a line joining the end of said arm and the axis of said applying cam, substantially as set forth.

In testimony whereof we have signed our names to this specification.

FREDERICK TASKER BURGESS.
CHARLES WILLIAM SEWELL.
